Patented Jan. 5, 1960

186,981

DIGITAL COMPUTER COMPONENT CASING OR SIMILAR ARTICLE

Robert A. Hughes, Reading, Mass.

Application May 1, 1958, Serial No. 50,691

Term of patent 14 years

(CL. D26—5)

FIG. 1

FIG. 2

Fig. 1 is a top plan view of a digital computer component casing or similar article, showing my new design, the bottom having substantially the same appearance; and

Fig. 2 is a perspective view thereof, the opposite side having substantially the same appearance and the opposite end being plain.

I claim:

The ornamental design for a digital computer component casing or similar article, as shown and described.
